UNITED STATES PATENT OFFICE.

HOWARD FORREST GORSUCH, OF COLUMBUS, OHIO.

STONE-CRUSHER.

1,002,261.

Specification of Letters Patent. Patented Sept. 5, 1911.

Application filed April 5, 1911. Serial No. 619,147.

To all whom it may concern:

Be it known that I, HOWARD F. GORSUCH, a citizen of the United States, residing at Columbus, in the county of Franklin and 5 State of Ohio, have invented a new and useful Stone-Crusher, of which the following is a specification.

This invention relates to an improvement in rock crushing machines, in which a plurality of movable jaws are employed.

The primary object of said invention is to provide a machine of this character in which the strain will be taken from the supporting frame, therefore, allowing said 15 frame to be made lighter, which is of great importance in crushing devices of the portable type.

A further object of said invention is to provide a plurality of movable jaws, said 20 jaws being actuated simultaneously, one of said jaws swinging on a pivot, the other jaw being bodily movable, having motion imparted to it at its upper and lower ends.

With the foregoing and other objects in 25 view which will appear as the nature of the invention is better understood, the same consists in the combination and arrangement of parts and in the details of construction hereinafter described and claimed, it being 30 understood that changes in the precise embodiment of invention herein disclosed can be made within the scope of what is claimed without departing from the spirit of the invention.

35 In the accompanying drawings: Figure 1 is a top plan view of the machine; Fig. 2 is a longitudinal section on the line 1—1 of Fig. 1; Fig. 3 is a side elevation with the truck and fly wheels removed; Fig. 4 is a 40 transverse section on the line 2—2 of Fig. 1; Fig. 5 is a transverse section on the line 3—3 of Fig. 1; Fig. 6 is a detail view showing the mechanism for returning the bodily movable jaw; Fig. 7 is a view similar to Fig. 2, the 45 jaws being in their closed position; Fig. 8 is a section taken on the line 8—8 of Fig. 7; and Fig. 9 is a detail perspective view showing a portion of the mechanism illustrated in Fig. 6.

50 The machine is positioned on a truck which is mounted on wheels 10 and 11 at its rear end, and the wheel 12 at its forward end, said wheels being arranged to support longitudinally disposed beams 13 and 14. 55 To the beams 13 and 14 are secured side plates 15 and 16 by means of bolts 17. A

shaft 18 extends transversely of and is supported by said plates at a point adjacent their forward ends, said shaft being provided with fly wheels 19 and the drive pulley 20.

Pivots supported at the rear end of the machine is a jaw 21 which is of the construction usually employed in such machines and which needs no detailed description, said 65 jaw being movable on a shaft 22 which is supported by the side plates 15 and 16. Spaced from said jaw 21 is a second jaw 23 which is bodily movable, its base portion being formed with a transverse slot 24 in 70 which is positioned the transversely extending roller 26, a bar 27 forming a bearing surface for said roller. This construction permits the base portion of the jaw 23 to move parallel with the supporting beams of 75 the machine.

Arranged on the shaft 18 is a pitman 28 which is actuated by the cam 29 as the shaft rotates. This pitman extends rearwardly of the machine and may be connected at 80 any of the points 30, 31, 32 to a lever 34, which lever is pivotally supported at the point 35 by the transversely extending shaft 36, the lever and pitman being disposed at the center of the shaft 18. The lever 34 is 85 provided with the re-curved end portion 37 and to this extension is secured a plurality of links 38, 38' and 39. The links 38 and 38' are pivotally supported at the points 38'' of the lever 34, the re-curved end portion of 90 said lever throwing said point 38'' in advance of the same, the link 39 being pivotally supported at the extreme end of said re-curved portion, this pivot point being slightly to the rear of the transverse shaft 95 36 when the lever 34 is in a vertical position. The links 38 and 38' are secured to the base portion of the jaw 23 and are capable when the shaft is rotated, of imparting a direct thrust to the lower portion of the jaw.

The link 39 extends between the links 38 and 38' and is pivotally connected to the end portion of a cam lever 40 which is illustrated in detail in Figs. 6 and 9. This lever or link 40 consists of the body portion 41, the 105 bifurcated end portion 42 which receives the end portion of the link 39 and extensions 43, which extensions are provided with trunnions 44, said trunnions connecting the member 41 with drive rods 45, said drive rods 45 110 extending rearwardly of the machine, their other ends being secured to trunnions 46

which extend from the upper portion of the jaw 21. The member 41 is formed adjacent its upper end with a cam face 46' which terminates adjacent its lower end in the 5 beveled face 47, the beveled face 47 contacting with a transversely extending rib 48 formed on the rear face of the jaw 23, said rib being rounded to reduce friction. A plurality of trunnions 49 extend from the 10 end portions of said rib, said trunnions extending within the elongated slots 50 of the links 51, which links are pivotally supported at points adjacent the upper end of the member 41.

15 In operation, as the shaft 18 draws the lever 34 to the position shown in Fig. 7, which is slightly forward of the position shown in Fig. 2, said lever will swing on its pivot 36 and by the peculiar curvature of the 20 end portion 37, the links 38 and 38' will be given a forward thrust, particular attention being called to the fact that this is a direct thrust, the bearing 26 facilitating this movement. As the link 34 is driven forward, the 25 member 40 will be forced upward through the medium of the link 39, its cam face on said upward movement contacting with the transverse rib 48 of the jaw 23, thus forcing said jaw to the position shown in Fig. 2.

30 This same upward movement carries the recurved end portion of the lever 40 back, thus exerting a pull on the connecting rods 45, this movement swinging the jaw 21 on its pivot and drawing the same toward the jaw 23 effectually crushing the rock which is 35 placed within said jaws. It will be noted that by this peculiar action, strain is taken entirely off of the side plates, the jaws and their toggle connections taking all of the 40 force of the crushing action. It will also be noted that the lower portion of the jaw 23 will advance with much greater force than the upper portion, said lower portion traveling in practically a line parallel with 45 the supporting beams, while the upper portion travels in an arc, the peculiar movement of the cam member 41 insuring this arcuate movement. When the shaft has revolved to the position shown in Fig. 2, the jaw 21 will 50 be returned to its normal position through the rearward movement of the connecting rods 45. It will be seen that when the lever 34 assumes the position shown in Fig. 2, the links 38 and 38' will draw the lower 55 end of the jaw 23 forward, its upper end being brought to the position shown in Fig. 2 by the links 51 which exert a forward pull on the trunnions 49. Thus, it will be seen that the crushing action is secured without 60 placing undue strain upon the frame or side plates.

What is claimed is:—

1. In a stone crusher, a pivoted jaw member, a bodily movable jaw member, means 65 for imparting a straight thrust to the lower

portion of said second member, means for moving the upper portion of said member in a curved path, and means for swinging the first mentioned member on its pivot.

2. In a stone crusher, a pivoted jaw, a 70 bodily movable jaw, means for consonantly moving said jaws, said means imparting a greater movement to the base portion of one of said jaws than to its top portion.

3. In a stone crusher, a pair of consonantly movable jaws, means for imparting a straight line thrust movement to the lower portion of one of said jaws, and cam means for imparting movement to the upper portion of said jaw. 75

4. In a stone crusher, a pair of consonantly movable jaws, means for imparting a straight thrust to the lower portion of one of said jaws, and means including a cam for imparting an arcuate movement to the upper portion of said jaw. 80

5. In a stone crusher, a pair of consonantly movable jaws, means for imparting a straight line movement to the lower end of one of said jaws, and a cam lever actuated by said means for moving the upper end of said jaw in a curved path. 90

6. In a stone crusher, a pair of consonantly movable jaws, means for imparting a straight line thrust to the lower portion of 95 one of said jaws, a cam lever actuated by said means to move the upper portion of said jaw in a curved path, said lever being connected to said upper portion by a plurality of pivoted links. 100

7. In a stone crusher, a supporting frame, a shaft supported by said frame, a cam lever secured centrally to said shaft, a lever pivoted adjacent said shaft, said levers being connected, a plurality of links pivotally connected to said second lever, a pivoted jaw, a bodily movable jaw, two of said links being connected to said bodily movable jaw at points adjacent its base, an offset extension formed integral with said second lever, a third lever, a link connection between said extension and said lever, said lever being capable of imparting an arcuate movement to the upper end of said bodily movable jaw. 110

8. In a stone crusher, a frame including 115 a plurality of supporting plates, a pivoted jaw supported between said plates, a bodily movable jaw supported between said plates, a drive shaft, a cam arranged on said drive shaft, a lever having operative connection with said cam, said lever being formed with an offset end portion, a plurality of links connecting said lever with the base portion of said bodily movable jaw, a second lever, a link connection between said second lever 120 and the offset extension of the first mentioned lever, said second lever being provided with a cam face, a rib formed on the upper portion of the bodily movable jaw, said rib terminating in trunnions, links piv- 125

130

totally supported by said second lever, said trunnions extending within slots formed in said links, and rods connecting said second lever with said pivoted jaw.

5. 9. In a stone crusher, a pivoted jaw, a bodily movable jaw, a cam actuated lever, a link connection between said lever and the base of said bodily movable jaw, a second lever, said lever being formed with a cam face, said cam face terminating in a beveled surface, a rib formed integral with said bodily movable jaw, a link connection between said lever and said jaw, and an operative connection between said lever and said 10 pivoted jaw.
10. In a stone crusher, a pivoted jaw, a bodily movable jaw, cam means for impart- 15

ing a direct thrust to the base portion of said bodily movable jaw, a pivoted lever, said lever being provided with a curved end 20 portion, said end portion being formed with a cam face, the lever when actuated imparting an arcuate movement to the upper portion of said bodily movable jaw, and a plurality of links carried by said lever for re- 25 turning said jaw.

In testimony that I claim the foregoing as my own, I have hereto affixed my signature in the presence of two witnesses.

HOWARD FORREST GORSUCH.
